DESIGN FOR A LUGGAGE BAG

James N. Hinson, Waterloo, Iowa, assignor to The Hinson Manufacturing Company, Waterloo, Iowa, a corporation of Iowa

Application August 22, 1940, Serial No. 94,564

Term of patent 14 years

To all whom it may concern:

Be it known that I, James N. Hinson, a citizen of the United States, residing at Waterloo, in the county of Blackhawk and State of Iowa, have invented a new, original, and ornamental Design for Luggage Bags, of which the following is a specification, reference being had to the accompanying drawings, forming part thereof.

Fig. 1 is a top plan view of a luggage bag in folded or closed position, showing my new design;

Fig. 2 is an elevational view of the right side of Fig. 1;

Fig. 3 is an elevational view of the left side of Fig. 1;

Fig. 4 is an end elevational view of Fig. 1;

Fig. 5 is a plan view of the inner face of the bag in unfolded position;

Fig. 6 is a plan view of the outer face thereof; and

Fig. 7 is an end elevational view thereof in unfolded position.

I claim:

The ornamental design for a luggage bag, substantially as shown.

JAMES N. HINSON.
